UNITED STATES PATENT OFFICE.

JOHN N. MURPHY, OF SPRINGFIELD, ILLINOIS, ASSIGNOR OF ONE-THIRD TO FRED H. BAKER, OF TULSA, OKLAHOMA.

SIPHON FLUSH-TANK.

1,298,549.

Specification of Letters Patent. Patented Mar. 25, 1919.

Application filed September 10, 1917. Serial No. 190,688.

To all whom it may concern:

Be it known that I, JOHN N. MURPHY, a citizen of the United States, residing at Springfield, in the county of Sangamon and State of Illinois, have invented new and useful Improvements in Siphon Flush-Tanks, of which the following is a specification.

My invention relates to improvements in siphon flush tanks.

The purposes of the invention are to provide a flush tank having a siphon structure integral with the body of the tank, and to provide means for controlling the flow of water through the siphon structure to induce siphon action to cause the water in the tank to be discharged through the siphon structure. The invention is illustrated in the annexed drawings, to which reference is hereby made and will now be fully described and the novel features thereof will be recited in the claims.

Figure 1 is a longitudinal sectional view of a flush tank and the siphon structure embodying my invention, taken on the line 1. 1. of Fig. 2. Fig. 2 is a top plan of the flush tank and accessories; and Fig. 3 is an enlarged vertical section on the line 3. 3. of Fig. 2. The ball cock is omitted from this view.

The same reference numerals designate the same parts in all the views.

The tank body 1 is preferably of cast metal. The tank-bottom 40 is preferably flat as shown. The end walls 41 and the side walls 42 are preferably erect relative to the bottom, as shown. The siphon structure is integral with the tank body and comprises a vertical member 2 and an unobstructed horizontal member 4. A vertical partition 3 divides the vertical member of the siphon structure into a water chamber 35 receiving water from the tank through the inlet opening 10 and an air chamber 36 in unobstructed communication with the interior of the horizontal member 4 of the siphon structure, said member 4 being adapted to effect free and unobstructed discharge of water through the nipple 6.

50 The preferred accessories used in conjunction with the siphon-structure will now be described.

The flanged nipple 6 occupies the opening 5 in the bottom of the tank; a packing ring

7 and a stuffing-box ring 8 surround the 55 nipple and are adapted to enter the opening 5. A nut 9 screws onto the nipple and upon tightening the nut, the ring 8 will press the packing 7 into the opening 5 to make water tight connection of the nipple with the tank. 60 A water-connection nipple 12 at the lower end of the main supply pipe 11 extends through the bottom of the tank and has direct communication with the source of water supply and with the interior of the supply 65 pipe. The supply pipe has a lateral member 13, Fig. 3. The body 14 of the self-closing faucet screws into the member 13. The intake pipe 29, (Fig. 1), screws into an elbow 28 on the supply pipe 11 and delivers water 70 under pressure from the supply pipe into the tank when the ball-cock 30 is open.

A ball-cock 30, of usual construction, communicates with the interior of the supply pipe through the opening 27 (Fig. 3). The 75 means for operating the ball-cock 30 comprises a lever 32 (Fig. 1), having a link connection with the handle of the ball-cock, a float 31 floatable on the water in the tank and a rod 33 connecting the float with the 80 lever 32.

A valve-seat member 15 having a circular flange 16 is located in the outer end of the member 13, and the inner end of the faucet-body bears against the flange 16 to hold 85 the part 15 firmly in place. The outlet member 25 (Figs. 1 and 3), of the self-closing faucet communicates with the chamber 36 of the siphon-structure through the opening 26 in the top of the siphon structure 90 in line with the air chamber 36. Packing 37 surrounds the member 25 and prevents leakage at the juncture of the cock with the siphon structure.

A block 20 (Fig. 3), extends through the 95 wall of the tank and screws into the body 14 and has at its outer end wedge-shape members 38. A valve rod 17 within the faucet-body extends outwardly through the block 20 and through the hub of the lever 100 21 and has at its inner end a plug 19 adapted to seat on the member 15. A spring 18 surrounds the valve rod and normally acts to hold the plug 19 against the seat-member 15. The hub of the operating-lever 105 21 has wedge-shape members 39 which engage the members 38 of the block 20 to cause the valve rod to slide outwardly in the block

during partial rotation of the lever. A washer 23 abuts against the hub of the lever 21. A screw 24 screws into the end of the valve-rod and connects together the parts 5 17, 21 and 23. Packing 34 in the block 20 surrounds the stem 17 and prevents leakage around the stem.

Operation.

- 10 In practice the supply pipe within the flush tank, being connected with the source of water supply as is usual, and the ball-cock 30 being open, water under pressure will flow through the supply pipe 11 and 15 the intake pipe 29 into the tank and thence through the opening 10 into the water-chamber 35 of the siphon-structure, until the water in the tank and in the chamber 35 reaches the level of the upper end of the 20 vertical partition 3; and thereupon the float 31, floating in the water in the tank, will cause the rod 33 to operate the lever 32 and connections to close the ball-cock 30, to stop the flow of the water. To discharge the 25 water from the tank, the lever 21 will be operated by hand to open the valve 19 to permit water from the supply pipe 11 to flow through the outlet 25 into the chamber 36 to expel air from the chamber and 30 thereby induce siphon action to discharge the contents of the tank through the outlet 6. When a sufficient quantity of water has been withdrawn from the tank, the valve 19 will close automatically to stop the outward 35 flow of water through the siphon-structure and permit the water from the supply pipe to flow through the pipe 29 into the tank to refill the tank; and so on as often as it may be desired to use the water in the tank and 40 refill the tank.

While I have herein described and shown the preferred embodiment of my invention, I do not wish to be limited strictly to the details of construction and arrangement 45 shown, as it is obvious that those details may be varied in many ways without departing from the broad spirit of my invention.

Copies of this patent may be obtained for five cents each, by addressing the "Commissioner of Patents, Washington, D.C."

Having thus described my invention, what I claim is:

1. The one-piece tank and siphon structure comprising a flat bottom, erect side walls and erect end walls integral with the bottom, a discharge opening through the bottom and intermediate of the length thereof, 50 an erect first siphon-member integral with one side wall and one end wall of the tank-body and having a top, a partition integral with the bottom and one side wall of the tank-body and with one side wall of the erect 55 siphon member, and dividing it into an air chamber and a water chamber, an inlet opening through one wall of the erect siphon member and communicating with the water chamber thereof, an opening through the top 60 of the erect siphon member and in line with the air chamber thereof; and a second siphon member integral with the bottom and one side wall of the tank-body and intercommunicating with the air chamber of the 65 erect siphon member and with the discharge opening through the bottom of the tank.

2. In a flush tank, the combination of the one-piece tank and siphon structure recited in claim 1; a supply pipe stationary in the tank-body and receiving water directly from the source of water supply; and a cock in communication with the supply pipe and having an outlet in line with the axis of the air chamber of the erect siphon member 75 of the one-piece tank and siphon structure.

3. In a flush tank, the combination of the one-piece tank and siphon structure recited in claim 1; a supply pipe stationary in the tank and receiving water directly from the 80 source of the water supply; a cock in communication with the supply pipe and having an outlet in line with the air chamber of the erect siphon member of the one-piece tank and siphon structure; and an intake 85 pipe in communication with the cock and delivering water into the tank.

JOHN N. MURPHY.
